UNITED STATES PATENT OFFICE.

ARTHUR MCLEAN, OF NEW YORK, N. Y.

AERIAL TURBINE-SHIP.

1,009,915.

Specification of Letters Patent. Patented Nov. 28, 1911.

Application filed January 6, 1911. Serial No. 601,086.

To all whom it may concern:

Be it known that I, ARTHUR MCLEAN, a citizen of the United States, and resident of New York city, in the county of New York and State of New York, have invented a certain new and useful Aerial Turbine-Ship, of which the following is a specification.

This invention relates to heavier than air aerial ships and has for its object an air ship that will not only rise and sail in the air, but will also have within itself means to prevent its too rapid descent in the event of the failure of the propelling mechanism.

The objects are attained by the means set forth in these specifications and the accompanying drawings.

Reference will first be made to the drawings, in which like letters and numbers refer to like parts in the several views.

Figure 1 is a side elevation of the aerial ship. Fig. 2 is an enlarged detail relating to the raising and lowering of the turbines. Fig. 3 is an enlarged representation of the means employed on the pilot turbine for raising and lowering and swinging the turbine sidewise. Fig. 4 is a detail showing the gearing for imparting opposite motions to the propellers of the turbines. Fig. 5, Sheet 2, is a plan of the aerial ship. Fig. 6 is a transverse section of one of the propeller bearings. Fig. 7, Sheet 3, is an end elevation of the aerial ship.

The main features of this aerial ship are the combinations of propellers which are together herein designated as turbines. The framing to which the turbines are shown attached, the engine for driving the turbines, the various appliances for manipulating the turbines and the general arrangement of the appliances, are shown in what may be regarded as only a tentative plan. In actual practice the parts, or most of them, may be disposed altogether differently than as herein shown, yet the results obtained will be substantially as herein described. Likewise it must be understood that the framing, for the most part here shown to be heavy, is all to be as lightly constructed, and of as light material as practicable to produce without neglecting the requisite strength and rigidity.

By reference to Fig. 1 it will be seen that within conical frames composed of base rings 54 and stanchions 11, are rotative shafts 7. To avoid obscuring other parts 55 the fronts of the base rings are omitted, but

the frame is shown in Fig. 5 without the propellers. On the shafts 7 are secured propeller screws 6, of uniform width of blades throughout their lengths. The shafts have 60 inner end bearings in the hubs 4 and 5, see also Figs. 2 and 3, and the outer ends of the shafts have bearings in the cone points 30. The shafts are rotated by means of the bevel gearing i , i^2 , Figs. 1, 2, 3, 5, 7. The 65 shafts are supported in the yoke frame m , Figs. 2 and 3 particularly, which comprises the hub 4, yoke arms 1, 1, hubs 2 and 3 and L hub 5. The hubs 2, 3 of the frames swing on shafts 22. The shafts 7 extend through 70 the hubs 4, and the ends are socketed in the L hubs 5, and the bevel wheels i are fast on the shafts 7.

Propeller screws g , formed as hollow spirals, are placed over the propellers f . 75 These outer propellers g are conical in their outer contour, being wide at the base with an upward taper, their internal diameters adapted to the diameters of the inner propellers. The small ends of the outer propellers have bearings 52 upon the shafts 7, and their large ends are screwed to the inside spur wheels 15. The attachment to the wheel is shown at 19, Fig. 1. These propellers are caused to revolve in a reverse 85 direction from the central propellers and, owing to their greater diameters, at one-half of the velocity of the central propellers. The means of accomplishing this result is shown particularly in Figs. 3 and 4. The wheel 90 15 is shown in partial section in Fig. 3, and in plan, also partly in section, in Fig. 4. The wheel 15 is loose upon the shaft 7, being maintained in place by a collar 72. A spur pinion 16 is fast on the shaft 7. 95 Upon the yokes m a stud 20 is secured, and upon this stud a pinion 17 travels, its teeth meshing with the teeth of the pinion 16 and the wheel 15. When the shaft 7 turns it causes the wheel 15 to turn in the opposite 100 direction, and having half the number of teeth of the wheel 15, the said wheel will move with half the velocity of the shaft. Thus, when motion is imparted to the shaft the propellers revolve in opposite directions, with this result: The inner propeller revolving in a direction to produce a downward current of air in the direction of the arrows s , Fig. 1, the outer propellers move a column of air in a like direction. The air moved by the inner propeller has a tendency 110 to move sidewise away from the propeller.

The outer propeller from the form of its construction and by reason of its open center, throws the air toward its center. The result is that between the two propellers the 5 air is concentrated into a column having a considerably greater pressure than the surrounding atmosphere, and consequently the propellers will rise upon the condensed air column. In other words, to express the 10 idea succinctly, the propellers produce a column of air pressure and climb up upon it.

To increase the capacity of the outer propeller to force the air centerward and downward, the blade is given a drooping curve 15 on its outer edges, as shown in Fig. 1. It will be plain that when the propellers are revolving rapidly the column of air pressure will not be limited to the confines of the propellers, but must extend considerably below them. This drawing is made upon a 20 scale of a diameter of eight feet for the large end of the outer propeller.

Fig. 5 shows that the plan herein described comprises three of the turbines, two 25 that are adapted only to be raised and lowered, and a third, a pilot, in advance of the other two, adapted not only to be raised and lowered as to its point, but to be swung sidewise to give direction to the movement 30 of the aerial ship.

Figs. 2 and 3 as already described, show how the turbines are swingable upon their bases on the shaft 22 in Fig. 3, which becomes the shaft 24 in Figs. 1, 5, 7, and in 35 Fig. 2 when applied to the rear turbines, wherein the shaft 24 sets transversely of the frame work supported in bearings r, r, r . This shaft drives the two turbines by the means shown in Fig. 2 and already de- 40 scribed.

The pilot turbine is arranged as in Fig. 3. The yoke m is pivoted in another yoke t having arms 6, 6, that support the pivotal shaft 22 for the yoke m . The bearing 12 has an 45 extension 12' underlapping the extension 8 of the yoke t . The two extensions are united by a pivot 8' Fig. 1, so that the yoke m swings sidewise on the pivot. This admits of the pilot turbine being swung to the right 50 and left, as per the broken lines in Fig. 5. To admit of this swinging the driving shaft 25 is united to the driver of the bevel wheel i' by a universal coupling 13, 14. The wheel i' drives the wheel i^2 .

55 The shaft 25 extends longitudinally of the frame, having its second bearing integral with the bearing 27' of the transverse shaft 24. The shaft 25 also drives the shaft 24 through the bevel gears i^1, i^2 . The shaft 25 60 is driven from the bottom of the frame by the engine h through a sprocket wheel 62 on the shaft 25, Figs. 1 and 5, the sprocket 61 on the engine shaft as in Figs. 1 and 7, and the sprocket chain 60, Figs. 1 and 7.

65 The main or engine shaft is provided with

a coupling 65, operated through levers 66, 67, 68, Figs. 1 and 5 for disconnecting the power from the turbines when necessary.

For swinging the pilot turbine from right to left, the yoke t is provided with lugs n , 70 Fig. 3, for the attachment of lines that are passed through guide pulleys 71, 71, Fig. 5, and to an overhead capstan 43, Fig. 1, with a hand-wheel 42, Figs. 1 and 5, for its manipulation.

For raising and lowering the pilot a separate capstan 57, with a hand wheel 58, Fig. 5, is provided. By means of lugs 32 and 33 on the ring 54, lines 47, 48 are attached, passed respectively over guide pulleys 41, 80 40 and 39, Figs. 1 and 5, and around the capstan 57. A like capstan 56, with a hand wheel 44, Figs. 1, 3 and 7, the drum 56 long enough for duplicate lines from the rear turbines, is connected with the lines 85 45, 45', Fig. 5, passing over guide pulleys 36, 36'. The lines are attached to the turbine frames at 34, Fig. 5. These capstans are shown in elevation in Figs. 1 and 7. The line connections are only indicated in the 90 latter figure by broken lines, this figure being given to show a bottom view of the turbines, and the turbines dropped to horizontal positions. They can be raised from any position from the horizontal to the vertical. 95

In descending from an elevation these turlines will offer such resistance to the atmosphere as to admit of a dropping at a speed controllable by the speed of the engine. In the event of the failure of the engine to 100 operate the resistance of the turbines to the atmosphere will be such as to cause them to revolve and impede a rapid descent. If the turbines remain coupled to the engine the work they perform in driving the engine 105 will still further lessen the speed of a descent.

The right is claimed to vary the forms of the propellers that comprise the turbines, and also, as has already been said, the forms 110 and arrangements of the operating means and devices shown so long as the scope of the invention is observed.

Having described my invention, what I claim and desire to secure by Letters Patent, 115 is—

1. The combination for aerial navigation, of three turbines mounted triangularly on a frame, a motive power within the frame with connecting means for driving the turbines, the turbines each comprising a supporting frame mounted on means for swinging the frames upon the centers of their bases, shafts mounted centrally and longitudinally of the frames, a screw propeller 120 fast to each of the shafts, and a screw propeller encircling each shaft propeller and having bearings upon the same shafts, the two propellers to revolve in reverse directions, one of the three turbines serving as a 125 130

pilot and adapted to swing sidewise, and means as windlasses at a central point within the main frame with connecting lines for controlling the positions of the three turbines.

5. 2. The combination for aerial navigation of a screw propeller on a rotating shaft, the screw blade comprising multiple convolutions around the shaft said screw blade of 10 uniform width throughout its length, and a second screw propeller around the said propeller with uniform blades, the outside propeller having a wide base and a uniform taper to its outer end, and means for revolving the two propellers in reverse directions.

15. 3. The combination for aerial navigation, of a screw propeller on a rotating shaft, the screw blade comprising multiple convolutions around the shaft, the screw blade of 20 uniform width throughout its length, and a second screw propeller encircling the said uniform propeller having bearings on the shaft of the first propeller, the said second propeller having a wide base of blade tapering to its outer end, means for revolving the 25 two propellers in reverse directions, the shaft of the said propellers having bearings in a swingable yoke, with means for raising and lowering and of swinging sidewise the 30 outer end of the said shaft, and gearing within the yokes for revolving the propellers at any angle.

4. The combination with a double propeller, that is, one propeller within the other, 35 of a propeller shaft supporting the propellers with means for rotating the propellers in reverse directions on said shaft, a vertically swinging yoke in which the propeller shaft has a double bearing, the said 40 vertically swinging yoke hinged to a side-

swinging yoke, a shaft uniting the two yokes, a gear wheel on said shaft engaging a driving gear wheel on the propeller shaft, the side-swinging yoke swiveled to a bearing of a main driving shaft, a coupling shaft 45 in said yoke and a gear wheel on the coupling shaft to engage with the wheel on the shaft that unites the two yokes, a universal coupling on the outer end of said coupling shaft, said coupling engaging with the said 50 main shaft, a bearing and support for said main shaft and a pivot on said support, the side swinging yoke supported and swingable on said pivot, and the vertically swinging yoke swingable on the shaft that unites the 55 two yokes.

5. A machine for aerial navigation comprising a frame, three propellers mounted upon said frame, two of the propellers side by side at the rear end of the frame, the 60 third propeller in advance of and midway between the two propellers, the propellers on rotatable shafts, the shafts supported in swivel supports, a motor attached with the frame, means for transmitting motion from the motor to the propellers, the propellers adapted to have their outer ends vertically swingable upon their swiveled base supports the forward propeller having an additional 65 sidewise swing, and means as capstans and connecting lines from the capstans to the supports of the propellers, for manipulating the propellers.

Signed at New York city in the county of New York and State of New York this fifth 75 day of January A. D. 1911.

ARTHUR McLEAN.
